UNITED STATES PATENT OFFICE.

JOSEPH SAXTON, OF WASHINGTON, DISTRICT OF COLUMBIA.

SEAL-PRESS.

Specification of Letters Patent No. 23,046, dated February 22, 1859.

To all whom it may concern:

Be it known that I, JOSEPH SAXTON, of the city of Washington, in the District of Columbia, have invented certain new and useful Improvements in Presses for Sealing and Securing Letters, Papers, or other Similar Matters, of which the following is a full, clear, and exact description, reference being had to the accompanying drawing, making 10 part of this specification, in which—

Figure 1 represents a perspective view of my improved sealing press, with its parts in the position they have just before forming a seal. Fig. 2, represents a vertical longitudinal section through the joint by which the arm carrying the stamp is properly adjusted, and Fig. 3 shows a vertical section through the guard.

All sealing presses previous to my invention, 20 have had for their object, a strong and somewhat sustained pressure, for the purpose of imprinting a device upon a plastic material, such as sealing-wax, or else upon a paper placed over a wafer. These require 25 for a sharp impression, a very considerable force and a comparatively slow motion, involving the necessity of great strength in the parts of the press, together with a very nice construction, especially for seals of great 30 size.

On the other hand the object of my improved press is, to form a seal according to my improved process of sealing, for which I have applied for a patent, which process consists, 35 essentially in placing a fusible metal or alloy, in the fluid state, upon the place of the seal, and by a sharp and quick blow, causing the said metal or alloy to penetrate the parts to be secured, while the device is 40 imprinted and the metal solidified, simultaneously.

For carrying out this process, I have invented a press which does not need the great solidity required in the presses used in the 45 ordinary mode of sealing and which I have arranged so as to be capable of rapid motion while at the same time I am enabled to provide a very simple and efficient means of adjustment for bringing the face of the stamp 50 or die into a proper position, which could not be used when great force was required. My press also allows ample room for conveniently putting the fused metal upon the article to be sealed, when in its place upon 55 the press, as well as space for the interval between the seal and the edge of the paper

or other matter to which it is to be attached. As no great amount of force is required I am enabled to make my press with a much lighter base than that required in ordinary presses and consequently this base may very advantageously be made the top of a receptacle for inclosing a drawer for containing the sealing material, a lamp for melting it, a basin in which to melt it, a spoon or ladle 60 for measuring it out in proper quantity— together with other means and appliances which may be deemed necessary in carrying out the process. Besides these peculiarities 65 which distinguish my sealing press from all others heretofore known I have also invented certain contrivances for facilitating the process of sealing with fused metals which will 70 hereinafter be described.

I shall now proceed to describe in detail the mode of construction of my improved press. The base (A,) may be made of any suitable material, such as well seasoned wood, and this may be made the top of a receptacle for inclosing a drawer containing 75 the various articles required, as above mentioned. Upon this base is firmly secured a standard (B,) terminating at its top in a hinge or joint (b,) upon which a lever (C,) turns freely in a vertical direction. The 80 other end of this lever is formed into a spherical enlargement or ball (c,) to which the arm (D,) carrying the stamp or die (S,) is attached, so as to be capable of adjustment, in the following manner. The ball is 85 provided with a vertical perforation through which passes a screw (E,) entering the upper end of the arm (D,) carrying the die (S,). This screw should be so much smaller in diameter than the perforation that the 90 arm may be turned in any direction required, without coming in contact with the sides of the hole. When great ranges of motion are needed the hole may be made conical 95 above and below. The object of this adjustment is, to bring the die horizontally upon the surface of the matter to be sealed, as 100 this latter varies in thickness.

The upper end of the arm is made cup shaped so as to adapt itself to the ball on the end of the lever. Above this ball is a cup shaped washer (F,) with a less radius of curvature than that of the ball, so that the screw (E) passing through it and into the arm, holds the latter against the ball, 105 in any required position, by the elasticity 110 of the washer. This washer may conven-

iently be made by striking it up from a plate of brass.

The arm (D) holds the die (S,) which may be screwed into it, or attached in any other proper manner.

In order to hold the letter or papers during the act of sealing, clamp springs (R, R,) may be attached to the base by screws or pins, on each side of the standard; the letter, being pushed under these springs, will be held firmly in the proper position. In sealing with fused metal if there is any excess of metal above that required for the seal, it is driven outward in all directions, and in order to retain this excess I make use of a guard (H) having a flat base where it is intended to bear upon the letter or matter to be sealed. If the internal surface of this guard came down perpendicularly upon the plane of the paper, the metal driven against it might be so forcibly checked, that it would adhere to, or cause a stain upon, the paper. To avoid this difficulty, I make the inner surface of such a form, that its vertical section is concave toward the seal, coming down to the paper so as to form an inclined plane of small angle, directed toward the seal, as is more particularly shown in Fig. 3. By this contrivance, the metal driven off from the seal is carried up the inclined plane and becomes solidified in the concavity of the guard. In order to facilitate the removal of this metal, the part of the base of the guard which projects inward, may be made a separate piece (h) spring into its place. This can readily be taken out and the solidified metal, which does not adhere, can then be removed. The guard also aids in holding and securing the matter to be sealed and therefore may be used without the clamp springs. Although I have shown this guard as not attached to the press, it may in many cases be deemed advisable to connect it to the base by an arm, hinged or jointed so that it may at once fall into its proper place.

Having thus explained the construction of my press, its mode of operation can readily be understood. The letter (L) or other matter to be sealed being placed upon the base, and if necessary, held by the clamp springs, the place of the seal is brought

under the die. As the object to be sealed varies in thickness, it becomes necessary to adjust the face of the die so that it shall strike when in a horizontal position. This is easily accomplished by means of the adjusting joint above described, the arm carrying the die being moved by hand into the required position, where it is held by the friction of the washer. The die being thus adjusted if necessary—the lever is to be thrown back, the guard put in its place and the fused metal deposited in sufficient quantity upon the part to be sealed. The lever is then seized by the hand, between the hinge and the ball and is rapidly brought down so as to throw the die upon the metal, which is made, by the force of the blow, to penetrate the parts to be sealed, and is then solidified, bearing a clear and sharp impression of the die or stamp. In this operation the momentum of the die is constantly increasing up to the instant when it comes in contact with the fluid metal which giving way before it absorbs the whole of the force, so that there is no rebound and the contact thus made and continued even a short space of time—by reason of the rapid communication of heat through the metal—insures the solidification of the whole mass of the seal. The length of the lever which enables me to give such a percussive action to form the seal, also furnishes a considerable distance between the place where the stamp strikes and the base of the standard—so that the seal may be placed at a distance from the edge of the paper, which in some cases may be a great convenience.

What I claim as my invention and desire to secure by Letters Patent is—

1. A sealing press operated by a lever to which the stamp is attached by an adjustable joint—the whole being adapted to the purpose of sealing with fusible metal or alloy, substantially as above described.

2. The guard for retaining the excess of metal driven off from the seal in the act of making the impression.

JOS. SAXTON.
